Primary Examiner — Keith J Wilson(74) *Attorney, Agent, or Firm* — SHIMOKAJI IP(57) **CLAIM**

The ornamental design for a booster fan, as shown and described.

DESCRIPTION

FIG. 1 is a front elevation view of a booster fan showing my design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view thereof;

FIG. 8 is another perspective view thereof; and,

FIG. 9 is a partial exploded view thereof.

The broken lines shown in the drawings depict portions of the booster fan that form no part of the claimed design.
